UNITED STATES PATENT OFFICE.

HAAKON P. HANSON, OF ALBERT LEA, MINNESOTA.

HAY-CARRIER.

1,261,522.

Specification of Letters Patent.

Patented Apr. 2, 1918.

Application filed November 27, 1916. Serial No. 133,692.

To all whom it may concern:

Be it known that I, HAAKON P. HANSON, a citizen of the United States, residing at Albert Lea, in the county of Freeborn and State of Minnesota, have invented a new and useful Hay-Carrier, of which the following is a specification.

This invention has reference to hay carriers, and its object is to simplify the construction of the hay carrier and to permit the lifting pulleys to be hoisted closer to the track than heretofore while the weight of the load is centralized, the whole structure permitting the employment of a very simple and efficient form of locking device.

In accordance with the present invention the lifting strand, which may be partly of rope and partly of chain, is caused to travel about a sheave having its axis of rotation diagonal to the hay carrier track, thus doing away with guides and sheaves heretofore employed, so that the lifting strand or rope is not crowded. Furthermore, the employment of a special locking device in connection with the arrangement of the sheave over which the rope travels permits the lifting pulleys to be hoisted closer to the track and to be located transversely of the track and centrally thereto, thus equalizing the weight on the track.

The locking device permits the use of chain where heretofore rope has been employed, and consequently wear is correspondingly reduced. The locking device 35 utilizes a rope clamp, connecting the rope and chain together, as a keeper for one member of the locking device with a latch structure and a fixed stop on the track co-acting to lock and release the lifting pulley structure automatically.

The invention will be best understood from a consideration of the following detailed description, taken in connection with the accompanying drawings, forming part 45 of this specification, with the further understanding that while the drawings show a practical form of the invention, the latter is not confined to strict conformity with the showing of the drawings, but may be changed and modified, so long as such changes and modifications come within the scope of the appended claims.

In the drawings:—

Figure 1 is an end elevation of the carrier with some parts broken away, the carrier track being shown in cross section.

Fig. 2 is a side elevation of a portion of the carrier with some parts broken away and in section, and showing the locking member in position just prior to engaging 60 the lifting strand at the rope clamp.

Fig. 3 is a view of the locking mechanism similar to the showing of Fig. 2, but with the parts in the locking position.

Fig. 4 is a perspective view of the lock 65 member for engaging the rope clamp.

Referring to the drawings, there is shown a track 1 and a hay carrier frame 2, both of which may, in the main, be of ordinary 70 form and need no particularly specific description. Mounted on the carrier frame 2 is a sheave 3 of a character to permit the passage of a rope 4 about it. The sheave 3 is mounted upon a pintle 5 carried by the frame 2 and arranged diagonal to the direction of travel of the carrier upon the track 1, the angle of diagonal displacement being about forty-five degrees more or less. Mounted in an offset portion 6 of the frame 2 is a guiding sheave 7 about which the rope 80 75 is carried, so that the rope after leaving the sheave 7 may extend lengthwise of the track 1, while between the sheaves 3 and 7 the rope has the same diagonal relation to the track as the sheave 3.

One end of the rope 4 is connected by means of a coupling 8 to one end of a chain 9, the other end of which is connected to a pin 10 or other part of the carrier frame 2 at a point opposite to that side of the sheave 3 about which the rope 4 passes.

The chain 9 is of such length that it sustains the compression pulleys 11 with the load connected to the hooks 12 on the frames 13 carrying the pulleys 11.

Secured in the frame 2 adjacent to the sheave 3 is a journal pin 14 upon which is mounted a rocker shaft 15 formed at one end with a rocker arm 16 extending in a direction substantially at right angles to the axis of rocking and at the other end formed with a lug 17 also extending at substantially right angles to the axis of rocking and on the opposite side of said axis to the arm 16. The lug 17 is provided with a shoulder 18 and has two adjacent surfaces 19 and 20 which may be appropriately curved for a purpose to be described. The arm 16 has pairs of fingers 21, 22 projecting from one face thereof near respectively opposite ends of the arm, the fingers of each pair being spaced apart and the spacing of one pair of fingers

from the other being somewhat greater than the length of the rope coupling 8, which, as shown in the drawings, is in the form of a metal cage having ends 23, 24 adapted to 5 lodge between the pairs of fingers 21, 22, as will hereinafter appear.

Fast to the track 1 and depending therefrom is a stop yoke 25 having legs 26, 27 spaced apart in the direction of the length of 10 the track.

Mounted in the frame 2 is a rocker 28 having a nose portion 29 and an adjacent surface 30 curved correspondingly to the surfaces 19 and 20 respectively. The rocker 15 28, which is in the nature of a latch member has a yoke portion 31 with legs 32, 33 adapted to engage the legs 26 and 27 in a manner to be described. When the load is being 20 lifted, and has about reached the limit of elevation, the parts may be assumed to be in the position shown in Fig. 2. Under these circumstances, the rocker member 15 is so positioned that the clamp or connector 8 may rise by the fingers 22 which are then 25 out of the path of the connector 8 and ultimately engage the fingers 21, the rope 4 in the meantime passing between the fingers 21. At the same time the leg 32 of the latch member 28 is lodged between the legs 26 and 30 27 of the fixed stop 25, while the nose 29 of the latch member 28 is resting upon the surface 19 of the lug 17 and the weight of the latch member 28 holds the rocker 15 in the position stated. The continued rising of the 35 connector 8 causes the end 23 thereof to engage the fingers 21 and as the point of engagement is to one side of the axis of rocking of the rocker 15, the latter is turned about its axis causing the fingers 22 to ride 40 into underriding relation to the end 24 of the connector 8 until further movement in that direction is stopped by engagement of the arm 16 with the chain 9. The rocking movement of the rocker 15 causes the lug 17 45 to move from under the nose 26 until the latter is no longer supported by the lug 17 and the rocker 28 gravitates toward the shoulder 18, the curved surface 30 then moving along the curved surface 20 and holding the rocker member against movement in a direction to carry the fingers 22 away from the underriding relation to the connector 8. The fall of the rocker or latch member 28 carries its leg 32 from between the legs 26 50 and 27 of the fixed stop member 25. These movements are all performed automatically and in quick order, so that the connector 8 becomes locked between and sustained by the fingers 21 and 22 of the arm 16 and the latch member 28 is released from the stop member 25, whereupon the frame 2 is drawn along 55 the track 1 by the continued pull upon the rope 4. When the structure is returned to the stop member 25, the leg 33 of the latch member 28 is then in the elevated position

with the leg 27 of the stop 25 in its path. The movement of the carrier frame 2 then causes the rocking movement of the latch member 28 in a direction to lift the nose 29 away from the shoulder 18 until finally the 70 nose 29 is above the end 19 of the lug 17 and the weight of the parts sustained by the chain 9 is sufficient to move the rocker shaft 15 and arm 16 to an extent withdrawing the fingers 22 from underriding relation to the 75 connector 8 whereupon the latter may drop with the rope 4 moving in the appropriate direction for the purpose.

The structure shown in the drawings is of extreme simplicity requiring but the presence of the diagonally mounted sheave 3 and the roller 7 to bring the compression pulleys crosswise of the track and eliminating guides and sheaves heretofore employed for the purpose. Moreover, the arrangement permits the lifting of the load to a higher elevation with respect to the track than heretofore and also permits the employment of a locking device of extreme simplicity and great efficiency. The use of the connector 8 90 permits the employment of chain where heretofore rope has been used, thus greatly reducing the liability of wear and offering stronger resistance to the effects of strains than is offered by rope, especially fiber rope. 95 The employment of the connector 8 permits the use of the holding member consisting of the rocker shaft 15, lug 17 and arm 16, with its fingers 21 and 22, and of the latch 28 with the fixed operating stop 25. 100

It will be understood that the connector 8 may be replaced by any suitable device capable of serving the same purpose so far as the locking structures are concerned.

What is claimed is:—

1. In a hay carrier, a sheave for the load carrying rope having its axis of rotation diagonal to the line of travel of the carrier, and a direction changing sheave associated with the first-named sheave for alining the 110 rope with the line of travel, said rope having a connection to the side of the carrier frame remote from the side of the first-named sheave over which the rope passes whereby the load carrying pulleys are positioned crosswise of and centralized with respect to the line of travel. 115

2. In a hay carrier having compression pulleys arranged crosswise of the line of travel, a sheave for the load carrying rope 120 having its axis of rotation diagonal to the direction of travel of the carrier.

3. In a hay carrier, a carrier frame provided with a sheave, a rockable lock member having a lug on one side of its axis of 125 rocking and a substantially pendent arm on the other side of its axis of rocking, with said arm having fingers spaced apart in the direction of the length of the arm and projecting laterally with respect to the length 130

of the arm, a latch member with a nose portion in operative relation to the lug and also provided with spaced lugs, a fixed stop member in the path of the latch member, and a load carrying rope extending about the 5 sheave and provided with a device for engagement by the fingers on the arm of the rockable member to sustain the load when the carrier is being moved, said arm rocking toward and from the sheave and located 10 above the bottom of the sheave.

4. In a hay carrier, a carrier frame with a rockable lock member having an arm on one side of its axis of rocking with fingers spaced apart lengthwise of the arm, and a lug on the other side of its axis of rocking, a latch member with a nose portion in operative relation to the lug and also provided with spaced lugs, a fixed stop member in the 15 path of the latch member, and a load carrying rope provided with a device for engagement by the fingers on the arm of the rockable member to sustain the load when the carrier is being moved, said hay carrier also having a sheave for the rope mounted on an axis diagonal of the line of travel of the carrier, and the rockable lock member being of a length and so positioned with respect to the sheave that the fingers on the arm may engage the device on the rope, and the lug on the rockable member and also the latch member for engaging said lug being out of the path of the sheave and the rope.

5. In a hay carrier, a carrier frame, an elongated rock shaft thereon having near one end an arm extending therefrom, and provided with fingers spaced apart lengthwise of the arm and near the other end having a lug extending from the rock shaft in the direction opposite from the arm, a rockable latch

member on the carrier having a nose portion for engaging the lug on the shaft to sustain the fingered arm on said shaft in either of two positions, said latch member being provided with spaced lugs, a fixed stop with spaced legs adapted to be engaged by the spaced lugs on the latch member for the operation of the latter, and a lifting rope on the carrier having a device for engagement with the fingers of the arm on the rock 45 shaft to be sustained and released by said fingers.

6. A hay carrier provided with a sheave for a load carrying rope with its axis of rotation diagonal to the direction of travel of the carrier, a lock structure on the carrier comprising a rockable lock member having its axis of rocking transverse of the line of travel of the carrier, and a rockable latch member for holding the lock member in either the locking or the unlocked position, a fixed stop member for actuating the latch member, a device on the load carrying rope for engagement by the lock member to sustain the load when the lock member is in the locking position, and a direction-changing sheave for the rope, with the latter having a connection to the side of the carrier frame remote from the side of the first-named sheave over which the rope passes, whereby load-carrying means may be positioned crosswise of and centralized with respect to the line of travel.

In testimony, that I claim the foregoing as my own, I have hereto affixed my signature in the presence of two witnesses.
